UNITED STATES PATENT OFFICE.

ARTHUR O. HUBBARD, OF MINNEAPOLIS, MINNESOTA.

COT-BED.

1,387,154.

Specification of Letters Patent.

Patented Aug. 9, 1921.

Application filed November 14, 1917. Serial No. 201,935.

To all whom it may concern:

Be it known that I, ARTHUR O. HUBBARD, a citizen of the United States, resident of Minneapolis, county of Hennepin, State of Minnesota, have invented certain new and useful Improvements in Cot-Beds, of which the following is a specification.

The object of my invention is to provide a bed designed particularly for the use of 10 soldiers at an army post or cantonment and also useful for campers generally and for hospital purposes or wherever a substantial bed of this type can be used.

A further object is to provide a bed which 15 will have no loose swinging parts when it is knocked down or folded which might be broken off and lost in transportation.

A further object is to provide a bed which can be folded into compact portable form 20 without separation of the parts and when unfolded or expanded will be extremely rigid and capable of withstanding the rough, hard usage to which a bed of this type is frequently subjected.

25 A further object is to provide a bed of strong, durable construction, which will be comparatively light in weight and easily transported from place to place.

The invention consists generally in various constructions and combinations, all 30 as hereinafter described and particularly pointed out in the claims.

In the accompanying drawings forming part of this specification,

35 Figure 1 is a side elevation of a bed embodying my invention,

Fig. 2 is an edge view showing the bed folded,

40 Fig. 3 is a bottom view of the bed unfolded, ready for use.

Fig. 4 is a bottom view of the bed folded and strapped together for transportation,

45 Fig. 5 is a transverse sectional view showing the position assumed by the rails and legs when the bed is folded,

Fig. 6 is a detail sectional view, showing the manner of mounting the legs on the side rail of the bed,

50 Fig. 7 is a transverse sectional view through one of the rails, showing the preferred manner of securing the flexible bed bottom to the side rails of the bed.

In the drawing, 2 represents a pair of side rails having longitudinal grooves 3 in their 55 outer faces to receive rods 4 which are inserted into loops 5 provided in the longitudi-

dinal edges of the flexible bed bottom 6, composed preferably of canvas or similar material. The upper edges of the rails are preferably curved to present rounded surfaces 7 on which the bed bottom rests. For securing the rods 5 within the grooves in the rails, I provide a series of spring washers 8 secured by suitable means, such as screws 9, to the rails and overlapping the grooves 3 and bearing on the loops of the bed bottom, thereby locking the rods in the grooves. When a load is placed on the bed bottom, the pull thereon will be imparted to the rods for drawing them against the upper walls of the grooves, the function of the spring washers being to hold the rods within the grooves and thereby the strain of the load will be transmitted to the rails. This is a very simple, economical means for 75 fastening the bed bottom in place, for by loosening the screws the bottom may be easily and quickly removed for substitution or repairs.

I provide the usual number of legs 10 for 80 these rails. These legs have angle plates 11 mounted on their upper ends and lapping by the outer faces of the rails 2 and connected therewith by pivot pins 12. These plates allow the legs to be swung inwardly and lie 85 against the under faces of the side rails, as shown in Fig. 2, the angle of said plates being such that when the legs are swung to their folded position they will be parallel and in contact with the side rails and fit 90 snugly thereon to allow the bed to be folded into compact form. The projecting ends of the plates have bosses 13 pressed therein and rivets 14 are mounted in the side rails and have heads for entering the recesses formed 95 by said bosses to hold the said legs in their open or unfolded position, there being sufficient spring to the metal ends of the plates to cause them to bear on the rivet heads with sufficient pressure to hold them in place. 100 When, however, the leg is grasped, it may be rocked back and forth on its pivot, the spring plates sliding over the heads of the rivets to allow the leg to be moved to its open or closed position.

105 Each leg is provided with an inwardly projecting lug 15 near its upper end and a similar lug 16 near its lower end. Links 17 are pivotally connected at one end with the lower lugs 16 and at their other ends are pivotally connected to bars 18 which in turn are pivoted to the lugs and at the point where the

bars 18 cross each other a pivot 19 forms a connection between them. These bars and links form in effect a toggle connection or joint which, when straightened, holds the 5 side rails of the bed apart and when broken, allows the rails to be moved together to the folded position of the bed. I prefer also to provide links 20 and 21 having their inner ends pivotally connected and their outer ends 10 pivoted at 22 to the bars 18 near their pivotal connections 15 with the legs. These links 20 and 21 also form a toggle for locking the bars 18 in their unfolded position, said links being capable of folding up, jack-knife fashion, as indicated in Fig. 4 for the purpose of 15 allowing the toggle bars and links to be folded in upon one another and the bed contracted to a compact or folded position. There are, of course, a pair of toggle links 20 and bars at each end of the bed between the 20 opposite legs at their front and rear ends and in setting up the bed, it is only necessary to draw the rails apart, straighten the toggle links 17 and 18 and lock them in their expanded 25 position by straightening the links 20 and 21.

I prefer to provide straps 23 mounted on the legs by means of loops 24 by means of 30 which the legs and rails may be bound securely together for transportation of the bed. When the legs are unfolded, the ends thereof will bear squarely on the under faces of the rails, as indicated in Fig. 6, and form a substantial support therefor, the legs being 35 swung out to a point where they will be slightly out of the perpendicular to prevent accidental collapse and spreading of the opposite legs will be positively prevented by the arrangement of the toggle bars and links 40 between them.

In various ways the details of construction herein shown and described may be modified and still be within the scope of my invention.

A bed of this type is particularly valuable 45 for army or camp use from the fact that there are no loose swinging parts, such as hooks or braces, when the bed is folded to be broken or torn off in transportation. Every member folds into compact form, the legs being held at both ends and prevented thereby 50

from swinging or swaying and becoming damaged when the bed is folded for transportation.

I claim as my invention:

1. A folding bed comprising side rails, a flexible bottom secured thereto, legs for said side rails, flange plates secured to the upper ends of said legs and embracing the corners thereof and projecting upwardly on each side of said rails and having a pivotal connection therewith at one side of the longitudinal axis of said legs, said plates having bosses formed therein, said rails having heads for entering said bosses for temporarily holding said legs in place and the upper ends of said legs being seated against the underside of said rails when said legs are unfolded. 55 60

2. A folding bed comprising side rails and a flexible bottom secured thereto, legs pivoted on said rails, bars pivoted one upon the other and having a pivotal connection at one end to one end of said legs and a pivoted link connection at their other ends with the other ends of said legs, and toggle links having their inner ends pivoted together and their outer ends pivoted on said bars, said links, when in alignment, locking said bars in their expanded position. 70 75

3. A folding bed comprising side rails and a flexible bottom secured thereto, legs for said side rails, said legs being mounted in the plane of said side rails to swing up against the under surface thereof when not in use and having their upper ends bearing on the under surfaces of said rails when turned down to a supporting position, bars pivotally connected with the upper portions of the opposite legs and projecting inwardly and having their inner portions pivoted together, and links pivotally connecting the inner ends 80 85 90 of said bars with the lower portions of the opposite legs for bracing and supporting the upper and lower ends of said legs when they are swung down to a working position, and toggle links connecting the upper portions of said bars and adapted, when unfolded, to lock said bars in their open position. 95

In witness whereof, I have hereunto set my hand this 2d day of November 1917.

ARTHUR O. HUBBARD.
